UNITED STATES PATENT OFFICE.

SOLOMON KAUFMAN, OF NEW YORK, N. Y.

COLLAR BUTTON.

Application filed June 30, 1926. Serial No. 119,580.

My invention relates to a new and improved form of collar button.

One of the objects of my invention is to devise a new and improved form of collar button in which a revoluble member is provided which can be held in the locking position and in the unlocking position so as to positively hold together the two tabs of a collar or to permit their ready separation.

Another object of my invention is to provide a simple and compact device which shall be cheap to manufacture and which will be reliable and efficient in operation.

Other objects of this invention will be set forth in the following description and drawing which illustrate a preferred embodiment of my invention, it being understood that the above general statement of the objects of my invention is intended merely to generally explain the same and not to limit it in any manner.

Fig. 1 is a central sectional view.

Fig. 2 is a top view.

Fig. 3 is an end view.

Fig. 4 is a front elevation.

Fig. 5 is a section on the line 5—5 of Fig. 1.

Fig. 6 is a view similar to Fig. 2 but showing the head of the collar button in the locking position.

The collar button comprises a body member 10 having a curved rear portion adapted to fit the contour of the neck. The body portion 10 has a recess 15 in which the shank 12 of the head 11 is mounted.

The shank 12 is preferably externally threaded and the wall of the recess 15 can also be internally threaded so as to cooperate with the external threading of the shank 12.

The underside of the head 11 is provided with four recesses 17 and these are adapted to be engaged by the detent 15 which is slidably mounted in the recess 14 of the body

10. A compression spring 16 actuates the detent 15 outwardly. Suitable stops of any well known kind may be employed for preventing the separation of the members 15 and 11 from the body 10.

When the device is to be inserted through the holes in the tabs of a collar, the head 11 is in the position shown in Fig. 2. After

the head 11 has been forced through the hole in the outer tab of the collar, it can be turned ninety degrees, as shown in Fig. 6. In this position it positively prevents separation of the tabs of the collar. Likewise, the detent 15 engages one of the four locking recesses 17 and prevents the turning of the head 11 to the position shown in Fig. 2, unless the head 11 is positively actuated by the user.

The recesses 17 are cup-shaped and the top of the detent 15 is correspondingly rounded so that the detent 15 can be forced inwardly when the head 11 is turned. This causes the detent 15 to automatically release and engage the respective recesses 17 when the head 11 is turned.

I have shown a preferred embodiment of my invention, but it is clear that numerous changes and omissions could be made without departing from its spirit.

Since the head 11 can be moved longitudinally with respect to the body 10 by merely turning the said head 11, the device is adjustable for varying thicknesses of collar tabs. The free outward movement of the detent 15 is sufficient to cause it to cooperate with the recesses 17, when the head 11 is moved inwardly or outwardly with respect to the body 10.

I claim:

1. A collar button comprising a body portion, a head revolubly connected to the body portion, and a detent adapted to releasably engage the head, to control the turning movement of said head.

2. A collar button comprising a body portion, a head having a shank revolubly connected thereto and a detent slidably mounted in the said head and associated with a compression spring, the said detent being adapted to releasably engage the inner face of the said head, said detent being laterally spaced from said shank.

3. A collar button comprising a body portion having a first recess provided with a threaded wall, a head having an externally threaded shank which is adapted to fit in the said first recess, the said head having a locking depression on the inner face thereof, and a detent slidably mounted in a second recess of the said body which is laterally

spaced from said first recess, a compression spring located in the said recess and adapted to force the said detent outwardly, the outer end of the said detent being adapted to re-
5 leasably engage the said depression.

4. A collar button comprising a body por-
tion, a non-circular head having a shank

which is revolubly connected to the body portion and a detent connected to the said body portion and adapted to releasably en-
gage the head, to control the turning move-
ment of said head. 10

In testimony whereof I affix my signature.
SOLOMON KAUFMAN.
